UNITED STATES PATENT OFFICE.

HERBERT T. HERR, OF MERION, PENNSYLVANIA, ASSIGNOR TO WESTINGHOUSE ELECTRIC AND MANUFACTURING COMPANY, A CORPORATION OF PENNSYLVANIA.

ELASTIC-FLUID TURBINE.

Application filed August 26, 1921. Serial No. 495,545.

To all whom it may concern:

Be it known that I, HERBERT T. HERR, a citizen of the United States, and a resident of Merion, in the county of Montgomery and State of Pennsylvania, have invented a new and useful Improvement in Elastic-Fluid Turbines, of which the following is a specification.

My invention relates to elastic fluid turbines, more particularly to the low-pressure blading thereof, and it has for its object to provide apparatus of the character designated which is efficient in operation, which is economical to construct, and which may be built in large units.

In the drawings, Figure 1 is a fragmentary longitudinal sectional view of an elastic-fluid turbine showing my improved low-pressure section applied thereto; Figs. 2 and 3 are views similar to Fig. 1, but showing modified forms of low-pressure sections; Figs. 4, 5, and 6 are detail views of portions of my improved blades; Fig. 7 is a sectional view along the line VII—VII of Fig. 1; and Fig. 8 shows a feature of my invention applicable to any of the modifications.

The size of an elastic-fluid turbine unit is limited by the capacity of the last row 30 of blades to pass large volumes of low-pressure elastic fluid; and, the capacity is limited, in the first place, by the permissible blade height in view of the centrifugal stresses, and, in the second place, by the efficiency of the last row, which, for a given blade height, is lowered as the outlet angles are made larger in order to pass large volumes of low-pressure elastic fluid.

In the re-issue patent of Karl Baumann No. 15,092, re-issued April 26, 1921, there is disclosed an elastic-fluid turbine having a low-pressure section in which the elastic fluid is divided into a plurality of annular portions, energy abstracting means or blades being provided for each portion, and each portion being expanded and discharged to the exhaust chamber. The low-pressure section of Baumann permits of the construction of relatively large turbine units, in that, his low-pressure section is capable of passing larger volumes of low-pressure elastic fluid than would be possible with the conventional last row of blading.

In the application of Henry F. Schmidt, Serial No. 482,768 filed July 6, 1921, and

assigned to the Westinghouse Electric & Manufacturing Company, and Alexander T. Kasley, Serial No. 486,517, filed July 21, 1921, and also assigned to the Westinghouse Electric & Manufacturing Company, there are disclosed new forms of low-pressure section blading which serve to increase the efficiency of an elastic-fluid turbine as well as to permit of the construction of larger units. The low-pressure blading, in these cases, is relatively wide and the elastic fluid is received at one side and is expanded and discharged at the tips or at the tips and at the other side, the tip or peripheral discharge permitting of the provision of adequate discharge area as well as of high effective blade speeds to utilize more effectively the kinetic energy of the elastic fluid. Also, as a discharge area at least as great as the area swept by the inlet edges of the blades may be provided, it is possible to provide the blades with small outlet or discharge angles, thereby improving the blade efficiency.

Accordingly, it is the object of my invention to improve the capacity of the blading of an elastic-fluid turbine section, particularly the last or low pressure section, over that possible in the turbines disclosed in the applications of Schmidt and Kasley or in the patent to Baumann, aforesaid. I accomplish this result by dividing the elastic fluid into a plurality of portions and providing a row of energy-abstracting elements for each portion which shall receive a portion of the elastic fluid at one side and discharge it at the tips or peripherally or substantially at right angles to the direction of in-flow. My construction is capable of handling relatively large volumes of low-pressure elastic fluid efficiently, and it is also relatively cheap and easy to make.

Referring to the drawings for a more detailed explanation of my invention, in Fig. 1, I show a turbine comprising a rotor 10 and a casing or cylinder 11 together with rows of stationary and moving blades 12 and 13, of any suitable type, for example, the reaction type, carried by the rotor and casing or cylinder, respectively. Elastic fluid is expanded and energy is abstracted in the rows of blades 12 and 13, and the last of the moving rows of blades 13 discharges elastic fluid for further expansion and energy abstraction in my improved low-

pressure section 15, from which the elastic fluid is discharged to an exhaust casing 16, in communication with a suitable condenser, not shown.

5 The low-pressure section 15 comprises a first row of stationary blades 17 provided with suitably arranged wall or partition elements 18 in order to divide the elastic fluid into distinct inner and outer portions, 10 the wall or partition elements being so inclined, cross-wise of the blades, as to define, with the blades, outer diverging or expanding passages and inner passages. The 15 blades 17 are followed by a row of moving blades 20 having outer energy-abstracting portions 21, preferably of the impulse type, adapted to receive elastic fluid, flowing from the expanding passages between the blades 17 at one side thereof and to discharge 20 it at the tips or peripherally. The blades 20 are provided with inner energy-abstracting portions 22, preferably of the re-action type, which are adapted to receive the inner portion of elastic fluid discharged from 25 the inner passages between the blades 17 and to abstract a portion of the energy therefrom. Thereafter, the inner portion of elastic fluid passes from the portions 22 of the blades 20 through a row of stationary 30 blades 23, where its direction and velocity are suitably modified for discharge between the relatively wide blades 24, adapted to receive elastic fluid at one side and to expand and to discharge it at the 35 tips or peripherally, or at the tips or peripherally and at the other side, to the exhaust chamber 16. The stationary row of blades 23 is supported by any suitable means 25 carried by the exhausting casing, 40 and the supporting means preferably extends a suitable distance beyond the tips of the blades 21 and 24 to prevent the intermixture of elastic fluid discharged therefrom, thereby obtaining a smooth discharge 45 and the substantial avoidance of eddy losses, which might otherwise occur due to cross-flow.

50 The outer expanding passages between the blades 17 for the outer annular portion of elastic fluid have a higher ratio expansion than the inner passages for the inner annular portion of elastic fluid, and the former are designed to expand the outer annular portion to the lowest practicable 55 point, thereby converting its pressure energy into velocity energy for action on the outer energy-abstracting portions 21 of the blades 20. The inner annular portion of elastic fluid is expanded sufficiently to maintain its 60 velocity at a suitable value for action on the blade portions 22, which are preferably provided—see Fig. 7—with sharpened inlet edges 27 and with trailing discharge edges 28 suitably designed and arranged, in accordance with the elastic-fluid and blade ve-

locities, to discharge elastic fluid in the proper direction and at the proper velocity to enter between the wide blades 24, a portion of the energy of the inner annular portion of elastic fluid being abstracted by the inner blade portions 22, the latter portions also being of such a contour as to provide a strong supporting structure for the outer impulse portions 21. The elastic fluid entering between the blades 24 is expanded 70 and discharged peripherally, the velocity energy acting reactively to impart mechanical energy to the blades.

75 In Fig. 2, I show a modified form of low-pressure section 30 employing stationary and moving blades 31 and 32, similar to the blades 17 and 20 of Fig. 1; but the row of blades 32 is followed by a stationary row of blades 33 having partition or wall elements 34 suitably inclined, crosswise thereof, to define, with the blades, outer expanding 80 passages and inner passages for the elastic fluid discharged from the inner portions of the blades 32; the partition or wall elements 34 serving to divide the inner annular portion of elastic fluid discharged from the inner portions of the blades 31 into further inner and outer annular portions, the outer annular portion of elastic fluid being expanded and having its pressure 85 energy changed into velocity energy for cooperation with the impulse portions 35 of the succeeding wide blades, and the inner annular portion being discharged in a suitable direction and at a suitable velocity for 90 cooperation with the reaction portions 36 of the wide blades. The inner annular portion of elastic fluid, discharged from the inner portions of the blades 33, enters between the wide blades below the inlet edges 95 of the impulse portions 35 and undergoes expansion and energy abstraction and peripherical or peripheral and lateral discharge as herein set forth and as set forth in the aforesaid applications of Schmidt and 100 Kasley.

105 In Fig. 3, I show a further modified low-pressure section 40 in which the first row of stationary blades 41 thereof discharges an outer expanded annular portion of elastic fluid for cooperation with the impulse corners 42 of the wide blades and an inner annular portion of elastic fluid for cooperation with the reaction portions 43 of the wide blades. The blade portions 42 110 and 43 receive elastic fluid at one side and discharge it peripherally as herein set forth.

115 The impulse portions 21, 35 and 42 of Figs. 1, 2, and 3, respectively, are similar and will be more clearly understood upon reference to fragmentary detail views, Figs. 4, 5, and 6. In Fig. 4, there is shown an impulse portion or bucket, which corresponds to the aforesaid portions, and it has an elastic fluid inlet edge 120

45 and a tip or peripheral discharge edge 46. The bucket is so shaped as to absorb velocity energy from the elastic fluid entering between the inlet edges and to 5 change the direction of flow of the elastic fluid from approximately an axial to approximately a radial direction.

The buckets may be so formed as to have portions thereof extending above and below the inner portions of the blades, as may be more clearly seen from Fig. 4. This provides for a better possible distribution of the mass of each bucket relatively to the blade carrying it as well as for a compact 15 and substantial assembly of the bucket portions.

Each bucket has an inner cut-away portion 47 at the front and a projecting rib 48 at the back; and, when assembled, the ribs fit into the cut-away portions, thereby providing for a rigid supporting of the impulse portions or buckets. As may be seen from Figs. 5 and 6, the buckets nest together to define elastic fluid passageways 25 as herein defined.

In order to reduce eddying in the buckets, I provide rounded corner lug members 49 which serve to guide the elastic fluid so that it may enter between the inlet edges, impart 30 energy to the buckets, and have its direction changed for peripheral discharge with little loss on account of eddying. Fig. 4 shows a guide member 49 extending inwardly diagonally from the outer inlet corner of the bucket. These guide members effectively prevent cross-flow of elastic fluid near the peripheral edges which, if allowed to take place, would, with the radially-flowing elastic fluid set up eddying.

It is to be understood that particular details of the impulse bucket may be varied to suit requirements of design or wishes relative thereto, so long as the essential 45 characteristics of my invention, i. e., receiving elastic fluid laterally and discharging it peripherally, are preserved.

It will be noted that the last-row wide blades in Figs. 1, 2, and 3, may be made of any suitable width in order to provide adequate discharge area for the elastic fluid and to preserve small outlet or discharge angles, whereby the blade efficiency may be maintained at a high value. As the elastic fluid is discharged peripherally, it is obvious that the reactive force of the expanding elastic fluid is applied thereto at points moving at high effective speeds, whereby 55 efficient conversion of kinetic energy into useful work takes place.

While Figs. 1, 2, and 3 show wide blades having the portions 24, 36, and 43 discharging peripherally, such portions may also discharge laterally, as shown in Fig. 8, and as disclosed in the aforesaid applications of Schmidt and Kasley.

The peripherally-discharging reaction portions of the wide blades shown in Figs. 1, 2, and 3 may be provided with curved ribs, for example, the ribs 45 in Fig. 1, which serve not only to strengthen the 70 blades but also to secure a change in direction of the elastic fluid with less eddying. These ribs are provided on the blades in any suitable manner, and the opposing ribs of adjacent blades contact to define curved 75 deflecting walls to gradually change the direction of flow of steam from an axial to a radial direction.

The operation of apparatus made according to the above, operates as follows: Elastic 80 fluid undergoes expansion and energy abstraction in the rows of blades 12 and 13 in the usual way, and is discharged from the last row of moving blades 12 for action in the low-pressure sections. In Fig. 1, the elastic fluid is divided into two annular portions by the wall or partition elements associated with the first row of stationary 85 blades 17, the wall or partition elements 18 and the outer portions of the blades defining expanding elastic fluid passageways 90 whereby the outer annular portion of elastic fluid is expanded to substantially exhaust pressure and is discharged at high velocity for impingement against the energy-abtracting elements or buckets 21, from which the elastic fluid is discharged peripherally or at the tips to the exhaust chamber 16. The inner annular portion of elastic 95 fluid is discharged from the passages defined by the partition or wall elements 18 and the inner portions of the blades 17, in a proper direction and at a suitable velocity for action on the inner portions 22 of the blades 20 which are so designed as 100 to abstract a portion of the energy of the inner portion of elastic fluid, the blade portions 22, at the same time, being suitably designed so as to constitute strong supporting structure for the outer energy-abtracting or impulse portions 21. The inner annular portion of elastic fluid is discharged from the blade portions 22 and passes through the stationary row of blades 23 where its direction and velocity are suitably modified for action upon the relatively 110 wide blades 24, between which the elastic fluid flows and is discharged at the tips or peripherally, or at the tips or peripherally and at one side to the exhaust chamber 16.

The operation of a turbine constructed in accordance with Fig. 2 is similar to that referred to in connection with Fig. 1, but the division of elastic fluid is carried a step further, that is to say the stationary blades 33 are provided with partition or wall elements 34 for the purpose of dividing the inner annular portion of elastic fluid discharged from the inner portions of the blades 17 into further inner and outer 125 annular portions.

nular portions, the outer annular portion being expanded and discharged at high velocity from the passages defined by the blades 33 and the wall or partition elements 34 for impingement against the energy-abtracting or impulse elements 35 integral with and forming parts of the wide blades, and the annular portion of elastic fluid being discharged from the passages defined by the 10 inner portions of the blades 33 and the partition or wall elements 34 at a suitable velocity and in a proper direction for expansion between the portions 36 of the wide blades and for discharge therefrom at the tips or 15 peripherally or at the tips or peripherally and at the other side.

From the foregoing, it will be seen that I have devised turbine sections in which the elastic fluid is divided into a plurality of 20 portions, each portion being adapted to give up its energy to separate energy-abtracting or blade portions arranged to receive elastic fluid laterally and to discharge it at the tips or peripherally or peripherally and laterally, whereby efficient blade portions may 25 be provided which are capable of accommodating large volumes of low-pressure elastic fluid, thereby permitting the construction of large and economically operating 30 turbine units.

While I have shown my invention in three forms, it will be obvious to those skilled in the art that it is not so limited, but is susceptible of various other changes and modifications without departing from the spirit 35 thereof, and I desire, therefore, that only such limitations shall be placed thereupon as are imposed by the prior art or as are specifically set forth in the appended claims.

40 What I claim is:—

1. An elastic-fluid turbine comprising an axial-flow portion followed by a peripheral-discharge portion comprising a plurality of 45 rows of energy-abtracting elements having continuous surfaces and having lateral inlet edges for receiving elastic fluid flowing in an axial direction and having peripheral discharge edges.

2. An elastic-fluid turbine comprising an 50 axial-flow portion and a peripheral-discharge portion comprising a plurality of rows of energy-abtracting elements having continuous surfaces, one or more of which 55 elements are of the impulse type, adapted to receive elastic fluid from said axial-flow portion.

3. An elastic-fluid turbine comprising a 60 portion having a plurality of rows of energy-abtracting elements having continuous surfaces; in which portion the elastic fluid flows in a single direction and a portion comprising a plurality of rows of moving energy-abtracting elements, said elements having inlet edges parallel to the discharge edges of the last row of energy-ab-

stracting elements of said first portion and peripheral discharge edges.

4. An elastic-fluid turbine comprising an energy-abstracting portion in which the elastic fluid flows in the same general direction, a portion receiving elastic fluid from the first portion and including a plurality of rows of energy-abtracting elements adapted to receive elastic fluid in the direction of flow of the first portion from the first portion and to discharge it substantially at right angles to said direction and means to keep the elastic fluid separate as it is discharged from two of said rows.

5. An elastic-fluid turbine comprising a 80 plurality of higher pressure stages, and a low-pressure section including a stationary row of blades adapted to receive elastic fluid flowing from the higher pressure stages; means cooperating with said blades to define outer elastic-fluid expanding passages, for expanding to exhaust pressure, and inner elastic-fluid passages; a row of moving blades having outer impulse portions 85 designed to receive elastic-fluid flowing in an axial direction, from said outer passages, to abstract velocity energy therefrom, and to discharge it peripherally, and having inner reaction portions; a row of stationary 90 guide blades receiving elastic fluid from said reaction portions; and a row of relatively wide blades adapted to receive elastic fluid flowing in an axial direction from said guide blades and to expand and discharge 95 it peripherally.

6. In an elastic-fluid turbine, a low-pressure section comprising means for dividing the elastic fluid into a plurality of portions and a row of peripherally-discharging 100 blades for abstracting energy from each portion.

7. In an elastic-fluid turbine, a low-pressure section having means for dividing the elastic fluid into two portions and peripherally-discharging, energy-abtracting elements 110 cooperating with each portion.

8. In an elastic-fluid turbine of the axial-flow type, a low-pressure section having means for dividing the elastic fluid into a 115 plurality of portions and peripherally-discharging, energy-abtracting elements cooperating with each portion.

9. In an elastic-fluid turbine, a low-pressure section having means for dividing the elastic fluid into a plurality of portions and energy-abtracting bucket or blade portions 120 cooperating with the portions adapted to receive elastic fluid at the sides and to discharge it at the tips.

10. In an elastic-fluid turbine, a low-pressure section having means for dividing the elastic fluid into a plurality of portions and a row of peripherally-discharging, energy-abtracting elements for each portion, one 125 row being arranged behind another.

11. In an elastic-fluid turbine, a low-pressure section comprising a plurality of rows of moving blades having continuous surfaces and adapted to receive elastic fluid at the sides and to discharge it at the tips. 5
12. In an elastic-fluid turbine, a low-pressure section having means for dividing the elastic fluid into a plurality of annular portions, peripherally-discharging energy-abs-
tracting elements for each portion, and means arranged between the energy-abs-
tracting elements for the portions to keep the elastic fluid separate as it is discharged therefrom. 10
13. In an elastic-fluid turbine, a low-pressure section comprising means for dividing the elastic fluid into a plurality of portions, energy-abstracting elements for one of said portions, and a row of blades adapted to receive another of said portions and to expand and discharge the latter substantially at right angles to the direction of receipt. 15
14. In an elastic-fluid turbine, a low-pressure section having means for dividing the elastic fluid into two or more portions and energy-abstracting elements cooperating with each portion and discharging substantially at right angles to the direction of flow thereinto. 20
15. In an elastic-fluid turbine, a low-pressure section having means for dividing the elastic fluid into a plurality of portions, peripherally-discharging impulse elements for abstracting energy from one of said portions and peripherally-discharging reaction elements for abstracting energy from another of said portions. 25
16. In an elastic-fluid turbine, a low-pressure section having means to divide the elastic fluid into two portions, a moving row of peripherally-discharging impulse elements for abstracting energy from one portion and one or more rows of reaction elements for abstracting energy from the other portion. 30
17. In an elastic-fluid turbine, a low-pressure section adapted to discharge elastic fluid substantially at right angles to the direction in which it flows thereinto comprising means for dividing the elastic fluid into a plurality of portions, impulse elements for abstracting energy from one of said portions, and reaction elements for abstracting energy from another of said portions. 35
18. In an elastic-fluid turbine having a plurality of stages, a low-pressure section comprising means for dividing the elastic fluid discharged from said stages into a plurality of portions and for expanding one of said portions to final discharge pressure thereby increasing its velocity energy, a row of impulse buckets for abstracting velocity energy from said expanded portion, and a row of blades adapted to receive another portion of the elastic fluid and to expand and discharge it peripherally. 40
19. In an elastic-fluid turbine, a low-pressure section designed to receive elastic fluid flowing in an axial direction and to abstract energy therefrom by means of a plurality of rows of tip-discharging blades having continuous surfaces and having lateral inlet edges. 45
20. In an elastic-fluid turbine, a low-pressure section designed to receive elastic fluid flowing in an axial direction comprising means for segregating the elastic fluid into inner and outer portions and a row of blades for each portion adapted to receive axially flowing elastic fluid, to abstract energy therefrom, and to discharge it radially or peripherally. 50
21. In an elastic-fluid turbine, a low-pressure section adapted to receive elastic fluid flowing in an axial direction comprising means for segregating the elastic fluid into inner and outer portions and for expanding the outer portion to exhaust pressure thereby increasing its velocity energy, a row of moving blades having outer impulse portions for abstracting velocity energy from said outer portion and inner reaction portions for abstracting energy from said inner portion of elastic fluid, and a row of peripherally-discharging blades for abstracting the available energy remaining in the elastic fluid discharged from said inner reaction portions. 55
22. In an elastic-fluid turbine, a low-pressure section comprising means for segregating the elastic fluid into inner and outer portions and for expanding the outer portion to exhaust pressure whereby its velocity is increased, impulse elements cooperat-
ing with said outer portion to abstract velocity energy therefrom, and a row of relatively wide blades for expanding and discharging the other portion peripherally. 60
23. In an elastic-fluid turbine having a plurality of axial-flow stages, a low-pressure section comprising means for segregating the elastic fluid received from said stages into inner and outer portions and for expanding the outer portion to a greater extent than the inner portion, peripherally-discharging impulse elements for abstracting energy from the outer portion, axial-flow reaction elements for abstracting part of the energy of the inner portion, and peripherally-discharging reaction elements for abstracting the remaining available portion of the energy of the elastic fluid discharged from said axial-flow reaction elements. 65
24. In an elastic-fluid turbine, a low-pressure section comprising a first row of stationary blades, means for dividing the blades into a plurality of portions having different ratios of expansion, impulse elements for abstracting energy from the elastic fluid 70
- 75
- 80
- 85

- received from the portion having the higher ratio of expansion, and reaction elements adapted to discharge peripherally for abstracting the available portion of the energy of the elastic fluid received from the portion having the lower expansion ratio.
25. In an elastic-fluid turbine, a low-pressure section comprising a first row of stationary blades, means cooperating with the blades for dividing them into portions having different ratios of expansion and for segregating the elastic fluid passing therethrough, peripherally-discharging impulse elements for abstracting energy from the elastic fluid flowing from the portion having the higher expansion ratio, and reaction elements for abstracting energy from the elastic fluid flowing from the portion having the lower expansion ratio.
- 20 26. In an elastic-fluid turbine, a low-pressure section comprising a first row of stationary blades, means cooperating with the blades for segregating the elastic fluid flowing therethrough into inner and outer portions, and a row of moving blades having outer peripherally-discharging portions for abstracting energy from said outer portion of elastic fluid and inner axial-flow portions for abstracting energy from said inner portion of elastic fluid.
- 25 27. In an elastic-fluid turbine, a low-pressure section having means for successively dividing the elastic fluid flowing therethrough into a plurality of portions, and peripherally-discharging, energy-abstracting elements cooperating with each portion.
- 30 28. In an elastic-fluid turbine, a low-pressure section comprising a plurality of rows of stationary and moving blades, one or more of the rows of stationary blades being divided to define portions having different ratios of expansion and the moving rows of blades having energy-abstracting portions adapted to receive elastic-fluid at one side and to discharge it at the tips.
- 35 29. In an elastic-fluid turbine, a low-pressure section comprising means for dividing the elastic fluid into a plurality of annular portions, a row of moving blades having tip-discharging, energy-abstracting portions for one annular portion and inner side-wise discharging energy-abstracting elements for another annular portion, a stationary row of guide blades for the last-named annular portion, and a row of tip-
- discharging blades receiving said last-named portion at one side.
30. In an elastic-fluid turbine, a low-pressure section comprising means for dividing the elastic fluid into a plurality of annular portions, a row of moving blades having tip-discharging, energy-abstracting portions for one annular portion, and inner, side-wise-discharging, energy-abstracting elements for another annular portion, a stationary row of 60 guide blades for the last-named annular portion, a row of tip-discharging blades receiving said last-named annular portion at one side, and supporting means for the guide blades provided with means to keep separate 65 the elastic fluid discharged from the rows of blades whereby eddy losses are minimized.
31. In an elastic-fluid turbine, a low-pressure section comprising a first row of blades, means cooperating therewith to segregate 70 the elastic fluid into inner and outer portions and to expand the outer portion to a lower pressure, a row of moving blades having outer energy-abstracting portions of the impulse type adapted to receive said outer portion at one side and discharge it at the tips and inner energy-abstracting portions, a stationary row of guide blades adapted to receive said inner portion and to direct it at the proper velocity and in the proper direction, and a row of relatively wide blades adapted to receive elastic fluid at one side from the guide blades and to discharge 75 it at the tips.
32. In an elastic-fluid turbine, a section 80 comprising means for dividing the elastic fluid into a plurality of portions and rows of energy-abstracting elements cooperating with the portions of elastic fluid including a row of tip-discharging elements.
33. A turbine blade comprising an impulse portion adapted to receive elastic fluid at one side and to discharge it at the tip and a reaction portion.
34. A turbine blade comprising an impulse portion adapted to receive elastic fluid at one side and to discharge it at the tip and a reaction portion adapted to receive elastic fluid at the same side and to expand and discharge it at the tip.
- 100 In testimony whereof, I have hereunto subscribed my name this 12th day of August, 1921.

HERBERT T. HERR.
